INVENTOR

Walter C. Runge,
BY *Clifton C. Holloway*

ATTORNEY

UNITED STATES PATENT OFFICE.

WALTER C. RUNGE, OF WEST COLLINGSWOOD, NEW JERSEY, ASSIGNOR TO DAVID L. SHORT, OF PHILADELPHIA, PENNSYLVANIA.

GARMENT-SUPPORTER.

1,219,162.

Specification of Letters Patent. Patented Mar. 13, 1917.

Application filed February 2, 1915. Serial No. 5,612.

To all whom it may concern:

Be it known that I, WALTER C. RUNGE, a citizen of the United States, and a resident of West Collingswood, county of Camden, 5 and State of New Jersey, have invented certain new and useful Improvements in Garment-Supporters, of which the following is a specification, reference being had to the accompanying drawings.

10 My invention relates particularly to that class of garment supporters in which an open loop formed of sheet material or wire is attached at its upper end to a supporting strap of elastic or other webbing and tapers to 15 ward its lower or free end, so as to securely engage in its constricted region the fabric of the garment to be supported, either by wadding said fabric and drawing it into the constricted lower end of the loop, or by the co- 20 operation with said loop of a button or stud which is carried by a companion strap and arranged to force the fabric into the loop and frictionally engage it in the said constricted lower end.

25 My invention is especially directed to means for preventing injury to the fabric of the garment to be supported, incident to its being drawn into the constricted region of the loop whereby it is supported.

30 The principal object of my invention is to prevent the direct contact of the fabric of the garment to be supported, with the hard and rigid edges of the supporting loop, by providing a flat thimble forming a jacket or sheath in which the loop is arranged to be clothed.

35 My invention, specifically stated, comprises a closed bag forming a jacket or sheath having a restricted opening or neck 40 at its upper end for the entrance of the loop, upon which said sheath may be loosely disposed so as to be readily removed therefrom, or it may be suitably attached at its upper end to the loop or its supporting strap.

45 My invention further comprehends a jacket or sheath having an elastic girdle adjacent to its open end, which tends to restrict the opening therein and which causes the walls of the jacket to closely hug the loop and frictionally engage said jacket therewith.

50 My invention also includes all of the various novel features of construction and

arrangement hereinafter more definitely specified.

55 In the accompanying drawings, Figure 1 is a front elevational view of a convenient form of my improved protecting sheath conveniently applied to the loop of a well-known type of stocking supporter, showing 60 a fragment of a stocking engaged therewith; Fig. 2 is a central vertical longitudinal sectional view of the assemblage shown in Fig. 1; Fig. 3 is a sectional view similar to Fig. 2, but showing the members illustrated in 65 Figs. 1 and 2 in the act of being engaged with the supporting loop of the garment supporter; Fig. 4 is a front elevational view of a modification of the sheath conveniently attached to a garment supporter; and Fig. 5 70 is a transverse section taken through the sheath *per se*.

75 In said figures, the garment supporter comprises the strap of webbing 5, which is itself looped to provide a hanger for the loop 6, and is extended therefrom to form the companion strap 7, at the termination of which is the frame 8 carrying the button or stud 9, which is co-operative with the open loop 6 to engage the stocking 10 in a well-known manner.

80 Various means have been devised whereby a web of suitable material is interposed between the fabric of the supported garment and the supporting loop of the garment supporter, to distribute the strain over an increased area of the stitches of said fabric and thereby prevent the possibility of slipping of the garment, or straining, tearing, or otherwise rupturing said stitches thereof.

85 In the present invention it is proposed to provide the loop 6 with a bag or sheath 12 forming a jacket in which the said loop 6 may be clothed so that said loop may be entirely invisible.

90 The sheath 12 is preferably formed of two similar webs of chamois forming the front and rear walls 13 and 14 respectively of the sheath 12, and having their perimeters joined by stitches 15 except at their top 100 edge, whereby a restricted opening is formed for the entrance of the loop 6, such opening being of such extent as to snugly fit the upper portion of the loop and be removably held thereon by friction.

105 Although the sheath 12 may be held by

friction on the loop 6, it is to be understood that it may be permanently secured in position to clothe the loop by securing it to the supporter by stitches 16, as shown in Figs. 5 1 and 2.

10 The sheath 12 may be of any desired contour, but it is found desirable that its body be sufficiently broad to provide ample fullness at the point of engagement with the garment to be supported within the opening of the loop, and that said body taper toward its restricted open end, as shown in Fig. 1.

15 It will be seen by an inspection of Fig. 2 that the rear wall 14 is thrust through the opening in the loop 6 and puckered with the garment to be supported, while the front wall 13 is bulged in a concave manner exterior thereto and serves to hide the unsightly wadding of the fabric or web due 20 to its being thrust through said loop.

25 In the engagement of the garment 10 with the loop 6, it has been found that the best results are attained by grasping the sheath and button 9 with the interposed garment between the thumb and finger and drawing them upward simultaneously, as best shown in Fig. 3, so that when said button is thrust through the eye 19 of the loop and then drawn down into the constricted slot 20, the 30 sheath 12 will not be distorted or pulled out of position.

35 The sheath 22 shown in Fig. 4 is provided with an elastic band 23 adjacent to its open end, and is thereby removably engaged with the loop 25.

40 I do not desire to limit my invention to the precise details of construction and arrangement herein set forth, as it is obvious that various modifications may be made therein without departing from the essential features of my invention as defined in the appended claims.

45 Having thus described my invention, I claim:

45 1. The combination with a garment sup-

porter having a loop for engaging said garment, of a sheath having an open end restricted, and having elastic adjacent to said open end tending to draw the walls of said sheath into frictional engagement with said 50 loop.

2. The combination with a garment supporter having a loop for engaging said garment, of a sheath having an opening in its upper end through which said loop is inserted, and means for attaching its open end with said supporter. 55

3. The combination with a garment supporter having a loop for engaging said garment, of a sheath having a restricted opening through which said loop may be inserted, and means for permanently attaching said sheath to said supporter. 60

4. An article of manufacture comprising a closed sheath for clothing the loop of a 65 garment supporter, and having a restricted opening at one end through which the loop is inserted.

5. An article of manufacture comprising a closed sheath for clothing the loop of a 70 garment supporter, and having a restricted neck at its upper end through which said loop is inserted, and a broadened body, one wall of which is arranged to be engaged in the opening of said loop, together with the 75 fabric of the garment to be supported.

6. An article of manufacture comprising a closed sheath for clothing the loop of a 80 garment supporter, and having a restricted neck at its upper open end through which said loop is inserted, and elastic means adjacent to its open end for frictionally engaging said loop.

75 In witness whereof, I have hereunto set my hand this 30th day of December, A. D. 85 1914.

WALTER C. RUNGE.
